(57) **CLAIM**

We claim the ornamental design for the display rotator for a kiosk, as shown and described.

DESCRIPTION

FIG. 1 is a perspective view of a display rotator for a kiosk showing circular holes formed in a top and bottom thereof, slots formed in front and back surfaces, transparent front, rear, top, and bottom surfaces, and opaque side surfaces, with the broken line showing for illustrative purposes only and forming no part of the claimed design;

FIG. 2 is a front elevational view of the display rotator showing the transparent front surface with slots;

FIG. 3 is a left side elevational view of the display rotator showing the opaque left side surface;

FIG. 4 is a top plan view of the display rotator showing the transparent top surface with the top circular hole;

FIG. 5 is a bottom plan view of the display rotator showing the transparent bottom surface with the bottom circular hole;

FIG. 6 is a right side elevational view of the display rotator showing the opaque right side surface; and,

FIG. 7 is a rear elevational view of the display rotator showing the transparent rear surface with slots.
